METHOD OF PRODUCING ELECTRICAL DISRUPTIVE DISCHARGES

Godfrey Steerup, Maywood, Ill., assignor to American Can Company, New York, N. Y., a corporation of New Jersey

Application April 24, 1931, Serial No. 532,450

4 Claims. (Cl. 250—34)

The present invention relates to an electrical disruptive discharge having improved characteristics and is more particularly directed to the production of a spark or arc having greatly increased effective spacial limits. In some respects the present invention is an improvement upon and refinement of my related application filed in the United States Patent Office Sept. 8, 1930, under Serial No. 480,601, for Electrical sterilization of objects or substances, now Patent No. 1,937,536, issued Dec. 5, 1933. The spark or arc of the present invention has all of the benefits of the spark of my former invention together with certain improved characteristics related to increased effective spacial limits.

The term "electrical disruptive discharge" is used in the present description to designate the arc, spark or kindred phenomenon associated with the passage of high tension electrical energy between separated electrodes of improved construction, the terms "arc" and "spark" in this connection being used in a broad rather than in a technical sense.

The present invention is further directed to the production of an electrical disruptive discharge having the full explosive or dynamic characteristics of a spark of high tension current and one, at the same time, which has greatly increased spacial limits. This new kind of spark or arc has many useful applications but in the following description special attention will be centered on the use of certain valuable actinic light waves of the ultra-violet wave length and the shorter wave lengths approaching the X-ray variety which will be considered for their bactericidal characteristics or, in other words, for their value in sterilization.

The principal object of the present invention is the provision of a novel method of producing an improved electrical disruptive discharge having increased spacial limits with resulting improved bactericidal characteristics.

An important object of the invention is the provision of an electrical spark or arc having accentuated explosive and dynamic characteristics induced in a simple manner and one in which there is a greatly reduced or only a relatively negligible amount of heat present.

A further important object of the invention is the provision of a method for producing an electrical spark or arc in which the wide band of light waves of different wave lengths are made highly penetrating and more available for effective use in electrical sterilization.

Numerous other objects of the invention will

be apparent as it is better understood from the following description, which taken in connection with the accompanying drawing discloses a preferred embodiment thereof.

Referring to the drawing:

Fig. 1 is a plan view partly broken away of the principal parts of an apparatus capable of producing the improved spark or arc of the present invention, a wiring diagram being appended thereto;

Fig. 2 is a longitudinal sectional view taken substantially along the line 2—2 in Fig. 1;

Fig. 3 is an enlarged transverse sectional view taken substantially along the line 3—3 in Fig. 1;

Fig. 4 is a view similar to Fig. 3 taken substantially along the line 4—4 in Fig. 1.

The improved spark of the present invention is of the open arc variety and in respect to area or extent (spacial limits) is analogous to a drawing out or increasing of the areas of the spark. Its spacial limits are greatly increased through the agency of sufficient vapors, resistance in leakage paths, and mechanical spreading by moving air currents but the improved spark is not decreased in its explosive effect. The term "effective spacial limits" as used in the present description indicates the combination of size or extent (spacial limits) of the spark together with the added function of bactericidal or destructive and explosive (effective) power.

In the drawing a form of apparatus is disclosed capable of producing such an improved arc or spark. Such an apparatus comprises a supporting frame 21 which is preferably of asbestos or other non-conducting material. This frame is cut away at 22 to provide an opening or recess for the electrical unit used in producing the spark or arc. The frame 21 may be connected with side walls 23 (Fig. 2) and a horizontal bed 24 over which an endless conveyor belt 25 may be moved for the purpose of conveying articles 26 through a sterilizing chamber 27 formed by said members 23 and 24.

The electrical unit comprises spaced, elongated, coextensive electrodes 31, 32 (see also Figs. 1 and 3) which are supported from the frame 21 by bolts 33. Both electrodes are in the same horizontal plane. Electrode 31 is formed with a vertical face 35 which is located directly opposite to a similar face 36 of electrode 32. These faces 35, 36 are angularly disposed to one another and are spaced relatively close together at one end of the electrodes but are further spaced apart at the other end (best shown in Fig. 1).

A comparison between Figs. 3 and 4 will disclose this space variation.

A series of bridge members 37 rest upon the top surfaces of the electrodes 31, 32, these members being spaced from one another and spanning the angular space between the electrode faces. Such members are preferably of thin strip form of insulating material, mica being suitable for this purpose.

10 A bar 41 of insulating material, a heat resisting glass such as pyrex being satisfactory, is located upon the bridging members 37 in alignment with the space between the electrode faces 35, 36. The members 37 support this bar 41 and one end thereof is preferably elevated above the upper surfaces of the electrodes 31, 32 (Fig. 3).

At the opposite end, the bar is depressed so that it rests partly within the slot between the 20 electrode faces 35, 36 the bridge member at this end being bowed as shown (Fig. 4). Straps 42 may be used for holding the bar 41 in its tilted position, these straps extending across the opening 22 being suitably connected with the frame 25 21 by bolts 43.

At the high end of the bar 41, this being adjacent the narrow space between the electrodes 31, 32, there is disposed an atomizer device comprising a pipe 45 terminating in a nozzle 46. This pipe is adapted to convey a mixture of air and water or other suitable liquid to the nozzle 46 from which it is projected as a mist or spray. As illustrated in Fig. 3, this nozzle directs the moisture spray against one side of the bar 41 and the film of moisture on the bar flows under capillary action and gravity along the bar to its lower end. Sufficient liquid is carried to all of the 30 bridging members 37 to provide moisture paths across the space between the electrodes, the bar 35 acting as a moisture distributing agent.

The moistened bridges 37, spanning as they do different spaces between the electrode faces 35, 36, are of different effective bridging lengths and this variation provides a condition which is utilized in the present invention. Electrical energy is caused to traverse these moisture paths in this 45 passage between electrode faces, electrical leakage paths of different lengths being thus produced. This will be more readily understood following the subsequent description in connection with the wiring diagram. The leakage area is increased spacially by the arrangement of electrodes and bridge members.

50 Adjacent one end of the electrodes 31, 32, preferably at the high end of the bar 41, provision is made for emitting a flow of air longitudinally of the electrodes and along the space gap between their faces 35, 36. For this purpose a pipe 55 48 is preferably inserted through the frame 21 of the apparatus and is bent inwardly at 49 to provide a nozzle for the air and to direct its flow longitudinally of the electrodes. This air is ejected from the end 49 under sufficient pressure 60 to insure flowing of the stream of air laterally of the bridging members 37. This causes the electrical disruptive discharges passing between the electrode surfaces and along the leakage paths to be spread out or increased, spacially. 65

70 This insures a more effective arc or spark. Reference should now be had to the wiring diagram in Fig. 1 which discloses the wiring for the electrical circuit used in the production of the improved arc or spark. Electrical energy 75 may be produced in any suitable manner as by a

generator 51 connecting electrically with a transformer 52. A wire 53 for this purpose leads from one side of the generator to a service switch 54 and a wire 55 connects the opposite side of the switch to a primary winding 56 of the transformer 52. The opposite end of this primary winding is connected by a wire 57 to the opposite side of the generator.

With the switch 54 in closed position, the electrical energy from the generator flows through the primary winding of the transformer and a secondary winding 61 in the transformer 52 has an induced electrical current imposed thereon which passes along a wire 62 which connects therewith to a binding post, which may be one of the electrode supporting screws 33, electrically connected with the electrode 32. In a similar manner a wire 63 connects the opposite side of the secondary winding of the transformer with a circuit breaker or interrupter 64 preferably of the rotary switch type, which is connected by wire 65 to a binding post in electrical communication with the electrode 31.

The air space or gap between the faces 35, 36 of the electrodes 31, 32 is too great to permit 25 passage of electrical energy between the electrodes by way of the air but after the bridging members 37 have been moistened, electrical leakage paths are established which, by reason of 30 the difference in effective lengths, are of different resistance, but all are of less resistance than the air. With electrical energy flowing in the primary circuit of the transformer 52 an induced current seeks to flow in the secondary circuit including the electrodes 31, 32.

The end bridging member 37, i. e., the one over the short space between the electrode faces, establishes the first leakage path and electrical energy jumps between the electrodes in an eruptive discharge of great intensity. The moisture in the leakage path at such time is immediately transformed into moisture vapor and is evaporated or otherwise dispersed by the discharge and further discharging along the dry path ceases. 40 The electrical energy seeking to break across the gap between the electrodes thereupon traverses the adjoining leakage path formed on the adjacent bridging member. The discharging phenomena is here repeated, the moisture in that leakage path being again dispersed by the spark. In like manner the third, fourth, etc. bridging members are utilized as vapor leakage paths for 45 succeeding discharges.

The effect of such discharge phenomenon, occurring in rapid succession and beginning with 50 the bridging member at the proximate ends of the electrodes and traversing the entire set of bridges up to the highest bridging member on the opposite ends, is to provide a succession of 55 electrical discharges having great dynamic effect and high penetrating value. Such sparks possess a remarkable number of effective light rays and numerous wave lengths, a large number being valuable for use as sterilizing agents 60 having valuable actinic rays.

By the time the last bridging member has been traversed with an electrical discharge, moisture has again built up in sufficient quantity over the first bridging member to reestablish a moisture 65 leakage path. This continues as to the other bridging members in a new cycle. These electrical discharges take place with great rapidity and while each discharge is distinct the general effect is analogous to a sheet of light resulting as 70 75

it does from summation of all of the electrical discharges along the electrodes.

During this time it will be recalled, sterilized air is flowing across the space between the electrodes and over the bridging members and this spreads out or laterally increases the spacial limits of the sparks or arcs as previously described. It is within the zone of this compound light sheet of light rays that any substances to be sterilized are subjected. Where such substances are articles 26, for example, they may be carried through the sterilizing chamber 27 by the conveyor 25.

It is thought that the invention and many of its attendant advantages will be understood from the foregoing description, and it will be apparent that various changes may be made in the steps of the process described and their order of accomplishment without departing from the spirit and scope of the invention or sacrificing all of its material advantages, the process hereinbefore described being merely a preferred embodiment thereof.

I claim:

1. The method of producing penetrating and sterilizing light waves, which includes the steps of atomizing water to form a leakage path, passing electrical energy along said leakage path as conductor thereby producing a discharge, and projecting a flow of air across said discharge to produce a spacial extension of said light waves.

2. The method of producing a succession of electrical discharges of increased effective spacial limits, which includes the steps of forming

a plurality of leakage paths of different lengths and different electrical resistances by atomizing water and imposing the spray within such leakage paths, successively passing electrical energy along successive leakage paths as conductors thereby producing a succession of discharges, and spreading said discharges transversely of said leakage paths.

3. The method of electrically sterilizing objects by means of a succession of electrical discharges of increased effective spacial limits, which includes the steps of forming a plurality of leakage paths of different lengths and different electrical resistances by atomizing water and imposing such spray within the leakage paths, successively passing electrical energy along successive leakage paths as conductors thereby producing a succession of discharges, spreading said discharges transversely of such leakage paths to produce a series of spaced penetrating and sterilizing light waves, and passing the objects to be sterilized into the zone of such penetrating light waves to sterilize the objects.

4. The method of electrically sterilizing objects which comprises producing an electrical arc having increased effective spacial limits by atomizing water to form a leakage path and passing electrical energy along said leakage path as conductor, projecting a flow of air across said discharge to further increase the spacial limits of said discharge, and passing the objects into the zone of said arc to sterilize the objects.

GODFREY STEERUP.
